UNITED STATES PATENT OFFICE.

CURT ROEMER, OF CHEMNITZ, GERMANY.

CLEANING DEVICE FOR TENTER CHAINS.

Application filed February 7, 1924, Serial No. 691,259, and in Germany April 17, 1923.

The cleansing of the chains of endless chain stretching, tentering and drying machines for fabrics is an operation consuming much time and labour, and is for this reason frequently dispensed with, with the result that the fabric treated is soiled and deteriorated.

The object of this invention is to provide an apparatus which automatically, easily, 10 quickly, conveniently and thoroughly cleans the joints of the chains, the cleansing agent being used economically and without deleterious effect on the fabric.

The improvement consists in providing 15 means for removing from the stretching chains the dirt particles accumulated thereupon in the course of working. The apparatus consists of feed and distributing devices, arranged on the stretching chain guide, for 20 supplying a suitable cleansing agent such as steam, air, gas mixtures or liquid under pressure to any number of the stretching chain only when the parts of the chain to be cleansed are facing the outlet orifices.

25 An example is illustrated in the annexed drawings, in which—

Fig. 1 illustrates the course of the stretching chain in a multi-stage stretching machine and the relation of the cleaning device 30 thereto,

Fig. 2 is a vertical section of the cleaning device and a portion of the chain,

Fig. 3 is a side view of the cleaning device itself, and

35 Fig. 4 is a top plan view of a portion of the chain, partly in section.

D designates the chain; the fabric to be fed to it is wound off the roll A, and the fabric is folded into a pile at B when it 40 leaves the chain.

Frequently hot air is introduced into the divisions I, II and III and the pressure of this air is liable to detach dirt from the stretching chains and carry it into the fabric, 45 which becomes soiled. At C is the device for cleansing the chain.

The cavities a, b indicated by oblique shading at the joints of the chain, are the parts where dirt accumulates and is difficult 50 to remove. Above the chain the cleansing appliance is arranged. It comprises a box 1, containing a distributing valve 2, which has ports c, d, e whereby the cleansing agent fed to the casing through the inlet f is allowed 55 at intervals to enter the valve, whence it flows through ports g and h to the parts a

and b. As indicated in Fig. 2 the inlet f is in connection with a steam pipe although it is obvious that any other suitable agent may be employed. The chain guide has a gap 60 through which the detached dirt falls into a receptacle 3.

If some solvent of dirt is to be added to the cleansing agent, this can be easily supplied with the cleansing agent through the 65 inlet f.

The distributing valve 2 may be rotated by means of the sprocket wheel 4 engaging the chain, and two spur wheels 5 and 6, the wheel 5 being fixed to the wheel 4. 70

What I claim is:

1. Means for cleaning a tenter chain, comprising a dispensing device for a cleansing fluid, a discharge outlet for said dispensing device terminating adjacent the 75 chain, and mechanical means for operating said dispensing device as each joint of the chain comes opposite the terminus of said discharge outlet.

2. Means for cleaning a tenter chain, 80 comprising a dispensing device for a cleansing fluid, a discharge outlet for said dispensing device terminating adjacent the chain, and means driven by the chain during its travel for operating said dispensing device as each joint of the chain comes opposite the terminus of said discharge outlet.

3. Means for cleaning a tenter chain, comprising a supply of cleansing fluid, a discharge outlet for said supply terminating 85 adjacent the chain, valve means for controlling said outlet, and means for actuating said valve means to open said outlet as each joint of the chain comes opposite the terminus thereof.

4. Means for cleaning a tenter chain, comprising a container for a cleansing fluid, a discharge outlet for said container terminating above the chain, a receptacle below the chain opposite said outlet, valve means for controlling said outlet, and means for actuating said valve means to open said outlet 100 as each joint of the chain comes opposite the terminus thereof.

5. Means for cleaning a tenter chain, comprising a supply of cleansing fluid, a discharge outlet for said supply terminating adjacent the chain, valve means for controlling said outlet, and means operated by the chain for actuating said valve means to open 110 said outlet as each joint of the chain comes opposite the terminus thereof.

6. Means for cleaning a tenter chain, comprising a fluid pressure supply, an outlet for said fluid pressure supply terminating adjacent the chain, and mechanically operated means for releasing said fluid through said outlet as each joint of the chain comes opposite the terminus thereof.
7. Means for cleaning a tenter chain, comprising a fluid pressure supply, an outlet for said fluid pressure supply terminating adjacent the chain, and means controlled by the chain in its travel for releasing said fluid through said outlet as each joint of the chain comes opposite the terminus thereof.
8. Means for cleaning a tenter chain, comprising a fluid pressure supply, an outlet for said fluid pressure supply terminating adjacent the chain, a revoluble member driven by said chain during its travel, and a valve controlling said outlet operated by said revoluble member, and opened thereby as each joint of the chain comes opposite the terminus of said outlet.

The foregoing specification signed at Dresden, Germany, this 19th day of December, 1923.

CURT ROEMER.
